UNITED STATES PATENT OFFICE.

ARTHUR W. CASH, OF DECATUR, ILLINOIS, ASSIGNOR TO UNITED STATES WIRE MAT CO., OF DECATUR, ILLINOIS.

DEVICE FOR THE KILLING OR DISABLING OF FLIES AND INSECTS.

1,369,757.

Specification of Letters Patent. Patented Feb. 22, 1921.

Application filed August 30, 1919. Serial No. 320,871.

To all whom it may concern:

Be it known that I, ARTHUR W. CASH, a citizen of the United States, residing at Decatur, in the county of Macon and State of Illinois, have invented a new and useful Improvement in Devices for the Killing or Disabling of Flies and Insects, of which the following is a specification.

My invention relates more particularly to 10 that class of devices commonly known as fly or insect killers, or swatters, and has for its object to provide an effective, elastic device, easy to manipulate and with small liability to mar or deface surfaces or objects with 15 which it may come in contact in usage, and further, to provide a simple, inexpensive article to manufacture, yet one having greatly extended lasting qualities.

In furtherance of these and other objects, 20 I have constructed a device as will herein-after be more fully described, and as illustrated in the accompanying drawings, in which—

Figure 1 is a plan view of one form of the 25 device as it may be economically manufactured for effective and lasting service. Fig. 2 is a plan view of another form of the device provided with cushioned edges to most effectually prevent marring or scarring of 30 surfaces or objects, also to facilitate fastening the extended ends of folded over corners of body member.

Fig. 3 and Fig. 4 are sectional views on 35 lines 3—3 of Fig. 1 and 4—4 of Fig. 2, showing method of attaching the overlapping clamping member to fixedly hold together the body and free diverging ends of handle in a manner to prevent twisting of the latter with respect to each other.

Fig. 5 and Fig. 6 show sectional views of 40 clamping device as applied to handle member at 5—5 on Fig. 1 and 6—6 of Fig. 2 respectively.

While these several figures illustrate the 45 preferred embodiment of my invention, various detail changes may evidently be made in the general form without departing from the scope of the invention and I do not wish to confine myself to the precise construction 50 as shown in the several illustrations.

Referring to the several drawings, the letters C—C, Figs. 1 and 2, represent the body member which is made of any suitable flexible material, such as wire mesh cloth and

D—D represent the flexible wire handle member of which F—F is the gripping portion thereof.

The sides of the handle member D converge from the looped gripping portion F to a central abutting position and passing 60 through clamp member B are fixedly clamped by the latter and thence continue to a junction with the body member at H whence they diverge and pass through clamp member J and terminate in free ends I—I. 65

Clamp member J overlies the lower triangular portion of body member C and is folded over at the ends tightly holding together the body member C and handle member D in fixed relation, also holding the free 70 ends I of handle D against twisting movement relative to each other and the parallel portions G.

It may be readily understood that the 75 tight clamping action of the part J, together with the tight fixed action of the part B, prevents twisting movement between the body member C and the handle member D, thereby maintaining the looped gripping portion F of handle always in the same 80 plane as that of body. This relative position of the two members permitting a maximum degree of flexibility, which is very necessary for maximum efficiency in operation of this device. 85

The folded over corner portions of the 90 rectangular body member C inclose and retain the free diverging ends I of handle member D. In addition to being fixedly held by clamp J, the folded over corner portions 95 are further secured to the main portion of the body member C by any suitable means such as stitching along the top edge of said corner portion as at E—E in Fig. 2, or the said corner portions may be folded farther inward and partially overlap each other as shown in Fig. 1 and be secured to main portion of body member by wire staples as at K—K.

The body member C as shown in Fig. 2 is 100 made with a cushioned edge of suitable material, such as felt, stitched in position; this cushioned edge further serving as an effective means to facilitate fastening the folded over corner portion to the main body portion as previously described.

Body member C as shown in Fig. 1 is provided with folded over edges only which

is not suitable for stitching to secure folded over corner portion to main body portion, hence the necessity for the further inward folding of the corner portion as shown in Fig. 1, and the different means of securing said folded over corner portion as before described.

Having illustrated and described my improvements in construction of devices for killing or disabling of flies and insects, I claim:

1. In a device for the killing or disabling of flies and insects, the combination of a flexible body member, and a flexible handle member composed of a single piece of wire formed with an open loop for the gripping portion, the sides of the loop then converging to an abutting central position, thence continuing parallel to a diverging point at its junction with the body member, the free ends of said handle member diverging at the same angle as that of the corners of the body member when folded back over the body, said corner fold inclosing the free diverging ends of said handle member, and a clamping member adapted to overlap one side of the body member at its junction with the handle member, the outer ends of said clamping member being folded over to fixedly hold the folded over corner portions of said body member to the free diverging ends of the flexible handle member, and means for securing the extended portions of the folded over corners of the body member.

2. In a device for the killing or disabling of flies and insects, the combination of a flexible body member and a flexible handle member composed of a single piece of wire or other suitable material formed with an open loop for the gripping portion, the sides of the loop then converging to an abutting central position, then continuing parallel to a diverging point at its junction with the body member, the free diverging ends of said handle member being inclosed within the folded over corner portions of the body member, and clamping members adapted to clamp and fixedly hold the abutting sides of the handle member at the point where they converge from the looped gripping portion and also overlying and fixedly clamping the folded over body portion to the free diverging ends of the handle member at the junction of said body and said handle members in such manner as to prevent twisting move-

ment between the two parallel sides of the handle member.

3. In a device for the killing or disabling of flies and insects, the combination of a flexible body member of substantially rectangular form, a flexible handle member composed of a single piece of wire or other suitable material bent to form an open loop gripping portion, the sides of the loop then converging to an abutting central position then continued in parallel lines to a diverging point at its junction with the body member, the free end of the handle member, then diverging at an angle the same as that of the folded over corner portions of the body member, the said free ends of the handle member lying in an inclosed position between the body member and the said folded over corner portions approaching and overlapping each other at a central line of the main body portion, clamping means for fixedly holding the two abutting sides of said handle member at its junction with the looped gripping portion and also at the junction of its diverging free ends with the body member, together with further means for suitably holding together the body member and the overlapping extended ends of the folded over corner portions thereof.

4. A device for the killing or disabling of flies and insects comprising a flexible body portion of substantially rectangular form, having two of its corners folded over upon itself at one end, the inner edges of said folded corners approaching each other near the central line of body, a flexible handle formed of a single piece of wire bent or looped at a point midway of its length to form a gripping portion, each end thence continuing to a point of junction with the body member, each free end from thence diverging outwardly between the body member and the folded over corner portions thereof, a rigid clamping member adapted to engage and fixedly hold together the body member and the diverging free ends of the handle member in such a manner as to prevent twisting movement between the two sides of the handle member, and between the handle and body members.

ARTHUR W. CASH.
